Primary Examiner — Cynthia M Chin(74) *Attorney, Agent, or Firm* — Egbert Law Offices, PLLC(57) **CLAIM**

The ornamental design for a pan lifter, as shown and described.

DESCRIPTION

FIG. 1 is an upper perspective view of a pan lifter showing my new design.

FIG. 2 is a top plan view thereof;

FIG. 3 is a bottom plan view thereof;

FIG. 4 is a side view thereof;

FIG. 5 is an opposite side view thereof;

FIG. 6 is front view thereof; and,

FIG. 7 is a rear view thereof.

The broken lines in the drawings represent environmental matter and portions of the pan lifter which form no part of the claimed design.
